DESIGN FOR A SUIT.

Application filed September 2, 1926. Serial No. 18,963. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Suit, of which the following is a specification, reference being had to the accompanying drawing, forming part thereof, wherein the suit is distinguished by the ornamental arrangement of pockets and belt adjacent the bottom part of the coat, the same agreeing in shape and appearance with

the collar, each being formed with a V structure.

Figure 1 is a front view of a suit, showing my new design.

Figure 2 is a view similar to Figure 1 but showing the collar open.

Figure 3 is a rear view of the suit shown in Figure 2.

I claim:

The ornamental design for a suit, substantially as shown and described.

TAUBE DAVIS.
